UNITED STATES PATENT OFFICE.

LEONARD WITTMAN, OF PITTSBURG, PENNSYLVANIA.

WASHING-MACHINE.

SPECIFICATION forming part of Letters Patent No. 359,195, dated March 8, 1887.

Application filed May 15, 1886. Serial No. 202,294. (Model.)

To all whom it may concern:

Be it known that I, LEONARD WITTMAN, a citizen of the United States, residing at Pittsburgh, in the county of Allegheny and State of Pennsylvania, have invented certain new and useful Improvements in Washing-Machines; and I do hereby declare the following to be a full, clear, and exact description of the invention, reference being had to the accompanying drawings, which form part of this specification.

This invention has relation to washing-machines, and relates particularly to that class of washing-machines wherein are employed a revolving corrugated or ribbed drum or roller arranged in a compartment or tub having a semicircular bottom and ribbed or corrugated slats or rollers, or both slats and rollers, fixed in proximity to the semicircular bottom of the tub or receptacle and parallel with the longitudinal axis of the drum or roller.

My invention has for its object the provision of means for maintaining an equable pressure of the revolving drum or roller upon the clothes or fabric being washed, and has for its further object the provision of means for readily and easily elevating the drum or roller should the clothes or fabric become too tightly packed between the revolving drum and the rollers or slats in the tub or receptacle.

My invention consists in the provision of novel means for journaling the revolving drum in the receptacle so as to permit of a certain amount of vertical movement of the same while preserving an equable or nearly equable pressure of the same on the material operated upon, as hereinafter claimed.

My invention further consists in the provision of novel means for raising the revolving drum and its bearings should the clothes or fabric become jammed or packed too tightly beneath said drum, as hereinafter claimed.

Referring to the accompanying drawings, Figure 1 is a side view of my improved washing-machine with a portion of one side broken away; Fig. 2, an end view of the same; Fig. 3, a top view, and Fig. 4 a detail view in perspective.

A A designate the sides of the receptacle in which the clothes to be washed are placed, and B the bottom of the same, which is semicircular in shape and properly secured to the

sides A A, the whole being supported upon legs a a a a. Within this receptacle or tub and close to the bottom B are fixed a number 55 of small corrugated or ribbed rollers, b b, which are journaled in semicircular or arc-shaped plates B', fixed on the sides A A. A number of ribbed or corrugated slats, b' b', are also fixed a slight distance from the bottom B, 60 and the said rollers and slats are arranged a short distance apart, so as to permit of free circulation of the washing-water.

The revolving roller or drum consists of two circular heads, C C, joined together by slats c 65 c c, which are set a short distance apart and are corrugated or ribbed on their outer surfaces, as shown. To the center of each of the heads C C is secured a boss or plate, C', which holds a shaft, E, said shafts serving as the 70 means for supporting the roller or drum and being journaled in suitable vertically-movable bearings, as will be presently described.

The sides A A of the receptacle are formed with vertical slots F F, through which pass 75 the shafts E E, and outside of the receptacle are fixed metallic plates G G, formed with vertical slots corresponding with the slots F F and with dovetailed flanges g g at their outer edges.

H H designate metallic plates having beveled edges which fit into the dovetailed flanges g g of the plates G G and having holes for the passage of the shafts E E.

A spiral spring, J, is secured to the plate H 85 on each side of the receptacle, and in front of each of the plates H is secured a plate, K, by means of bolts k k, one above and the other below the shaft E. Upon one side of the machine the shaft E carries a cog-wheel, L, that 90 engages with a larger cog-wheel, L', whose shaft l projects out through the outer plate, K, and has an attached crank, M, with a handle, m, at its end, the crank and the intermeshing cog-wheels serving as a means for imparting rotary motion to the drum or roller. A spiral spring, J, is also secured to the roll or drum bearing on this side, and the said spiral springs serve to draw the roller or drum down toward the rollers and slats in the receptacle, the 100 plates H H sliding freely in the dovetail flanges g g in the plates G G.

A frame, N, having lever-arms m' m', is pivoted to the sides of the receptacle at n n, and

the ends of the lever-arms $m' m'$ are formed with hooked ends $m^2 m^2$, which hook under the upper bolts connecting the plates G G and H H. A lever, O, having a handle, o, is pivoted 5 at p to the end of the receptacle and engages with a rack, Q, on one of the legs a, and the said lever is connected by a wire, cord, or chain with the pivoted frame N and provided with a retractile spring, R, so that upon depressing 10 or elevating the handle o the bearings on each side of the receptacle will be correspondingly elevated or depressed, and the roller or drum thereby moved vertically and, when the lever O is engaged with the rack Q, held in such 15 position.

Having fully described my invention, I claim—

1. In a washing-machine employing a rotary drum and a receptacle therefor, the combination, with the receptacle having slots in its 20 sides, and the plates G, vertically slotted and formed with dovetailed flanges g g, of the ro-

tary drum, its shaft, the plates H H, through which said shaft passes, and the spiral springs J, secured at one end to the plates H H and 25 at the other to the receptacle, substantially as and for the purpose described.

2. In a washing-machine, the combination, with a suitable receptacle and a rotary drum supported in vertically-movable bearings on 30 each side of said receptacle, of the frame N, pivoted at n to the sides of the box and having the hooked ends engaging with said movable bearings, the pivoted lever O, connected to said frame, the rack Q, with which said lever 35 engages, and spring J, all constructed and arranged substantially as described.

In testimony that I claim the foregoing I have hereunto set my hand this 12th day of May, A. D. 1886.

LEONARD WITTMAN.
